A. BEASLEY.
EQUALIZING SIDE FRAME AND JOURNAL BOX.
APPLICATION FILED SEPT. 16, 1918.

1,306,461.

Patented June 10, 1919.

Inventor:
Arthur Beasley
By John C. Higdon
attorney.

UNITED STATES PATENT OFFICE.

ARTHUR BEASLEY, OF EAST ST. LOUIS, ILLINOIS.

EQUALIZING SIDE FRAME AND JOURNAL-BOX.

1,306,461.

Specification of Letters Patent. Patented June 10, 1919.

Application filed September 16, 1918. Serial No. 254,307.

To all whom it may concern:

Be it known that I, ARTHUR BEASLEY, a citizen of the United States, residing at East St. Louis, in the State of Illinois, have 5 invented certain new and useful Improvements in Equalizing Side Frames and Journal-Boxes, of which the following is a specification containing a full, clear, and exact description, reference being had to the accompanying drawings, forming a part hereof.

My invention relates to improvements in car truck side-frames and journal-boxes, and it consists in the novel construction herein- 15 after described and claimed.

The object of my invention is to provide a construction wherein the side-frames and journal-boxes may "equalize" the load upon the journals in an improved manner, and 20 thus prevent undue friction and wear.

A further object is to provide an improved emergency means, which will prevent separation of the journal-box from the side-frame, as for instance in the derailment of 25 the car, and which will not interfere in the least with the efficient "equalization" function of the side-frames and journal-boxes, although readily permitting the removal and replacement of a damaged journal-box.

30 In the drawings,

Figure 1 is a side-elevation, partly in section, of one end of a car-truck side frame and its journal-box.

Fig. 2 is a transverse section of same, the 35 section being taken on the line 2-2 of Fig. 1.

Fig. 3 is a vertical section taken on the line 3-3 of Fig. 1, looking in the direction indicated by the arrows.

Fig. 4 is a perspective view of the journal- 40 box removed.

Fig. 5 is a detail perspective view of the locking key used in securing the journal-box to the side-frame, and

Fig. 6 is a detail perspective view of a 45 gravity lug or dog that is used in connection with the said key.

The numeral 1 designates the ordinary car-wheel mounted upon the axle 2 having the usual journal 3.

50 The numeral 4 designates the journal-box, which may be of the usual construction, although in the present illustration of my invention I have shown upon its top a transverse semi-circular bearing-recess 5 located 55 between the parallel top ribs 6 of the box; and upon the opposite sides of said box at

the ends of said semi-circular bearing-recess I have formed integral vertical locking-lugs 7, which project at a right angle from the sides of the box, and extend downwardly 60 thereon but a slight distance below the said semi-circular recess 5, so that the pedestal jaws 8 of the side-frame 9 may have an unobstructed movement upon the sides of said box, the latter being devoid of the usual 65 pairs of vertical guide flanges between which said jaws are located in ordinary truck construction.

The said side-frame 9 is provided with a cylindrical journal 10 formed integral therewith and extending longitudinally thereof, and located in the said semi-circular bearing 70 5 of the said box.

The pedestal-jaws 8 of said side frame are provided in their faces with a vertical 75 groove 11, whereby (in assembling the parts or in removing the box) the said locking-lugs 7 may pass from the lower ends of said grooves into a segmental recess 12 located at the upper end of said grooves, and 80 swing laterally of said frame in said segmental recess during the practical use of the truck upon a railroad track.

A flat locking-key 14 has an integral head or flange 15 formed on its outer end, and is 85 inserted beneath said locking-lug 7 (at one side of the box) through a key-way 16 formed laterally in the inner pedestal-jaw of said frame, and thereby prevents the accidental separation of the frame and jour- 90 nal-box.

To prevent the accidental withdrawal of said key 14 from its key-way 16 in said frame, I form an L-shaped depression 17 in the underside of said key near the inner end 95 of the latter, and locate a gravity dog 18 in said depression at the time said key is inserted, so that when the key reaches the limit of its inward movement the said dog will rotate in said depression and the outer 100 end of said dog will fall until it rests against the inner side of the adjacent pedestal-jaw 8, and thereby prevent the withdrawal of said key until the projecting arm of said dog is turned upward and replaced in its 105 former position in the said depression.

I prefer to use but one key for each journal-box, but if desired two could be provided, and in order that one pattern of box may answer for a truck and avoid rights 110 and lefts I have formed lugs 7 on both sides of the box.

For a similar purpose, both jaws 8 of the side-frames are provided with the vertical grooves 11 and segmental recesses 12.

The numeral 19 designates the usual "brass" which rests upon said journal 3, and 20 indicates the usual wedge.

The operation will be readily understood without further description.

I claim:

- 10 1. A car-truck side-frame having pedestal-jaws, one of which is provided with a vertical groove at the upper end of which is a segmental recess and a horizontal key-way; a journal-box; a rocking bearing between
- 15 said box and said side-frame, whereby the box and frame may relatively rock and equalize; a locking-lug at the side of said box located to move in said segmental recess of said frame; a horizontal locking-key in
- 20 said key-way beneath said locking-lug; and

means for preventing the withdrawal of said key during the operation of the truck.

2. A key for locking the journal-boxes of car-truck side-frames to said frames, consisting of a piece of metal having in one side 25 near its inner end an L-shaped depression, and an L-shaped dog which occupies said depression while said key is being placed in position, but which rotates after the key is placed until one arm of said dog gravitates 30 to a position in which it engages the frame and prevents the withdrawal of said key until said arm is replaced in said depression.

In testimony whereof I have signed my name to this specification in presence of two 35 subscribing witnesses.

ARTHUR BEASLEY.
